CLAIM

The ornamental design for a bumper component, as shown and described.

DESCRIPTION

FIG. 1 is a top, front and right side perspective view of a bumper component showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

A second embodiment of the claimed design for the bumper component is a mirror image of the bumper component as shown in FIGS. 1 to 7.

1 Claim, 4 Drawing Sheets
